(57) **CLAIM**

The ornamental design for a fishing lure, as shown and described.

DESCRIPTION

FIG. 1 is a drawing of a front view of my new design for a fishing lure; and

FIG. 2 is a drawing of a rear view thereof; and,

FIG. 3 is a drawing of a top view thereof with the side flutter blades removed and wherein the bottom view is identical. The material shown in dashed line comprises no part of the novel design.
